CLAIM

The ornamental design for a portable holographic projection device and power bank accessory set, as shown and described.

DESCRIPTION

FIG. 1 is a front perspective view of a portable holographic projection device and power bank accessory set, showing my design;

FIG. 2 is a front view of the portable holographic projection device and power bank accessory set illustrated in FIG. 8; FIG. 3 is a rear view of the portable holographic projection device and power bank accessory set illustrated in FIG. 8; FIG. 4 is a left side view of the portable holographic projection device and power bank accessory set illustrated in FIG. 8;

FIG. 5 is a right side view of the portable holographic projection device and power bank accessory set illustrated in FIG. 8;

FIG. 6 is a top view of the portable holographic projection device and power bank accessory set illustrated in FIG. 8; and,

FIG. 7 is a bottom view of the portable holographic projection device and power bank accessory set illustrated in FIG. 8.

The broken lines are directed to environment and are for illustrative purposes only and form no part of the claimed design. The thin solid lines illustrate surface contour and form no part of the claimed design.
